3 Claims. (Cl. 242—45)

ABSTRACT OF THE DISCLOSURE

A controller for adjusting the torque of a winding motor connected to a support member, the torque being adjusted in response to the amount of material wound upon the support member, the controller comprising a guide means for applying material to be wound on the support member, said guide means being adapted to temporarily actuate a switch after a predetermined amount of material has been wound upon the support member, a reversible, high slip motor connected to the switch, means for controlling the power input to the motor, and means connecting the high slip motor and the means for controlling the power input to the motor so that upon each operation of the high slip motor adjustment is made to vary the power input to the motor in relation to the amount of material wound upon the support member.

This invention relates to apparatus for controlling the power output of a motor means.

Although, for the sake of brevity, this invention will be described relative to the winding of filament upon a spool or support member, it should be noted that this invention is broadly applicable to motor controller means in general.

Heretofore, in order to control the tension on a filament or the like being wound on a spool the torque of the motor turning the spool has been controlled by varying the voltage input to that motor in response to the thickness of filament wrapped upon the spool. Heretofore, the voltage has been varied by mechanical means employing a rider arm which contacts the surface of the filament on the spool and which rides upwardly as that thickness increases. The use of rider arms or other means in contact with the surface of the wound filament is undesirable in many aspects since the rider arm must necessarily interfere directly in the winding operation in the area of the rapidly rotating spool. Further, such rider arms provide mechanical interference when starting the winding operation on an empty spool and when removing a full spool.

It has now been found that a suitable control means which does not contact directly the wound filaments nor interfere directly with the winding operation but which still accurately controls the spool driving motor in response to the amount of filament wound on the spool is effected when there is employed a guide means for uniformly applying material to the support member (spool) which guide means is associated with a switch means and is adapted to periodically and temporarily actuate the switch means after a predetermined amount of material has been placed upon the support member. The switch means is in turn operatively connected to a reversible, high slip motor capable of dynamically braking itself and of being installed indefinitely in the braked position. The high slip motor has associated therewith means for operating same for a finite period of time after each temporary actuation of the switch means and also is operatively connected to an adjustable means for controlling the power input to the motor means which drives the support member. Thus, upon each separate operation period of the high slip motor, in response to the temporary actuation of the switch means by the guide means, the adjustable means

is adjusted to vary the output, e.g. increase the torque, of the support member drive motor as the amount of filament wrapped upon that support member changes, e.g. increases.

Accordingly, it is an object of this invention to provide a new and improved apparatus for controlling the power output of a motor means.

Other aspects, objects and the several advantages of this invention will be apparent to those skilled in the art from the description, the drawings, and the appended claims.

In FIGURE 1 there is shown a system embodying the apparatus of this invention.

In FIGURE 2 there is shown an electrical system for operating the apparatus of FIGURE 1.

In FIGURE 1 spool 1 is operatively connected through shaft 2 to gear 3. Gear 3 is meshed with gear 4 which gear is operatively connected to drive motor 5 through shaft 6. Motor 5 can be any conventional constant torque, i.e. the torque varies with the applied voltage motor such as that made by Howell Electric Motor Company, Howell, Mich. A preferred motor has the following specifications: 32 oz./ft. torque, synchronous r.p.m.—1200, three phase, 60 cycle, 440 volts, .83 amp.

A level winding guide means generally shown as 7 is supported on top of frame 8 and is composed of a cylinder 9 having therein a piston 10 and means for reciprocating said piston from one end of cylinder 9 to the opposite end and back again. Such reciprocation means are well known in the art and therefore not shown but, for example, can employ alternating air pressure supplied through conduits 11 and 12 in a conventional manner. Piston 10 carries horizontal support arm 13 to the opposite end of which is connected vertical support arm 14. Arm 14 has attached thereto rotatable guide member 15 over which filament 16 is guided prior to being wound upon spool 1.

Thus, in operation, as spool 1 is rotated by drive motor 5 piston 10 is reciprocated within cylinder 9 so that guide 15 passes back and forth along the full length of spool 1 thereby laying down successive uniform layers of filament. Piston 10 also carries a trip arm 20 which is adapted to contact and temporarily actuate microswitch 21 which is fixed to end 22 of section 9. Switch 21 is operatively connected through electrical conduits 23 and 24 to the automatic voltage control unit 25 which will be explained in detail with reference to FIGURE 2.

Control unit 25 is operatively connected through electrical conduits (not shown) to stepping (high slip) motor 26. Control unit 25 is adapted, upon temporary actuation of switch 21 to operate stepping motor 26 for a finite but adjustable length of time after which stepping motor 26 is stopped until switch 21 is again actuated.

Stepping motor 26 can be any type of conventional motor which is instantly reversible, i.e. can drive a member in either a clockwise or counter clockwise manner at any time, high slip dynamic braking, i.e. can be made to stop itself immediately upon being taken out of circuit, motor. Two presently primary requirements for such a motor is that it can be promptly reversed in its direction of rotation and it can be dynamically braked while its windings remain energized.

The dynamic braking is effected by putting the windings that rotate the motor drive shaft in both directions in phase so that they instantly buck one another, stop the motor's rotation and thereafter maintain it stopped even though the windings remain energized. To restart the motor a phase lag is reimposed between the windings.

A preferred type of motor is the type K-2 produced by the Bodine Electric Company, and, more particularly, is the type KCI-22RM-B826E-1800M which has a speed

of 0.7 r.p.m. and operates on 115 volt alternating current. This type of motor employs a capacitor between its clockwise rotating windings and its counter clockwise windings so that when the capacitor is taken out of the circuit the clockwise and counter clockwise windings are put in phase and the motor dynamically brakes itself and can be kept in this stalled position for an indefinite time notwithstanding the fact that its windings are still energized. Other similar motors having the same characteristics of operation can be employed.

Stepping motor 26 is operatively connected mechanically or otherwise through shaft 27 to adjustable means 28. Adjustable means 28 can be any conventional means for controlling the voltage or other input to motor 5, e.g. a variable resistor, an autotransformer, and the like. Adjustable means 28 is operatively connected to motor 5 by electric conduits 29 and 30.

A microswitch or microswitches 31 are operatively connected to control unit 25 and to stepping motor 26 through arm 32 so as to limit the extent of rotation of shaft 27 in either the clockwise or counter clockwise direction especially upon resetting of the adjustable means 28 after a first spool 1 has been filled, removed, and a second empty spool 1 has been placed on shaft 2 and is ready to be filled with filament 16.

FIGURE 2 shows shaft 27 of stepping motor 26 operatively connected to gear 40 which in turn is matched with gear 41 which gear is fixed to shaft 42. Shaft 42 rotatably carries contact arm 43 which is in electrical contact with resistor 44. Electrical conduits 45 and 46, 47 being the basic on-off switch for the system, are connected to motor 5, resistor 44, and shaft 42.

By conventional electrical means (not shown) when motor 5 is operating, coil 50 of relay 51 is energized which energization transfers switches 52 and 53 from their normal positions against contacts 54 and 55 into position against contacts 56 and 57. Thus, current is passed from hot line 58 through lines 59, 60, and 61 to rectifier 62. Rectifier 62 converts the alternating current to direct current and can be any type of conventional rectifier such as International Rectifier Type 5A6. The direct current is passed through line 63, switch 64, line 65, switch 21 and line 67 to charge capacitor 68. Capacitor 68 can be of any conventional type, for example a 40 microfarad unit operating on 350 volts direct current. Switches 69 and 70 in relay 71 are normally in the position shown in FIGURE 2. Thus, line 72 which bypasses capacitor 68 is disconnected from the circuit while capacitor 68 is being charged.

When microswitch 21 is tripped by follower 20 on piston 10 as shown in FIGURE 1 it transfers from contact 73 to contact 74 thereby allowing capacitor 68 to discharge through lines 75 and 76 and energizes coil 77 of latching relay 71. At the same time current also passes from line 75 through line 78, variable resistor 79, which can also be a conventional resistor-capacitance time delay means well known in the art, and line 80 to neutral line 81. The time period during which coil 77 is energized by the discharging capacitor 68 can be varied by varying the resistance interposed by resistor 79 between lines 78 and 80. Since the energization of coil 77 transfers switches 64, 69, and 70 to contacts 82, 83, and 84, respectively, this time period during which the discharging capacitor energizes coil 77 also determines the time period during which relay 71 is switched from its normal position.

Upon switching relay 71 from its normal position switch 64 is opened so that no charging of capacitor 68 can take place even when switch 21 returns to its normal position against contact 73. Also upon switching 71 from its normal position switch 69 is moved against contact 83 and closes the circuit comprising the discharging side of capacitor 68, line 72, switch 69, line 85, and line 76 so that coil 77 remains energized by discharging capacitor 68 notwithstanding the fact that switch 21 has been returned

to its normal position against contact 73 by movement of follower 20 away from microswitch 21. Thus, although switch 21 is only temporarily actuated and then released coil 77 remains energized for the full time period which capacitor 68 is capable of energizing that coil.

Further, upon switching of latching relay 71 by energization of coil 77, switch 70 moves against contact 84 thereby providing a circuit comprising hot line 58, line 86, switch 70, line 87 and coil 88 to relay 89. Thus, closure of switch 70 due to energization of coil 77 energizes coil 88 which in turn causes switch 90 to move from its normal position against contact 91 into position against contact 92. Movement of switch 90 against contact 92 breaks the short circuit composed of line 93, switch 90 and line 94 about capacitor 95 of motor 26.

As explained above as one example of this invention motor 26 is that type of motor which requires a capacitor between two of its windings in order to operate and which, when that capacitor is removed from the circuit, locks in position, i.e., dynamically brakes itself and holds itself in that position until the capacitor is once again put into the circuit. Therefore, by energization of coil 88 and opening of switch 90, capacitor 95 is put back into the circuit of motor 26 and therefore that motor starts into operation. Being a low revolution per minute motor shaft 27 turns slowly and therefore contact arm 43 moves along in contact with resistor 44 equally as slowly, causing an incremental change in resistance in series with motor 5 which in turn causes an incremental change in voltage to and torque from motor 5.

Capacitor 95 is maintained in circuit between lines 96 and 97 of motor 26 until coil 88 is deenergized, at which time switch 90 automatically returns against contact 91, by the movement of switch 70 off of contact 84. The movement of switch 70 back to its normal position, as with switches 64 and 69, occurs automatically when coil 77 is deenergized by the charge on capacitor 68 decaying to a point where it can no longer adequately activate or energize coil 77.

Thus, it can be seen that motor 26 will operate for a finite period of time depending upon the charge on capacitor 68 and the rate at which that charge is allowed to decay through coil 77. Furthermore, it can be seen that the frequencies of the periods of operation of motor 26 are determined by the frequencies of actuation of switch 21 by follower 20 on piston 10 of level winder 7. Therefore, as piston 10 moves away from end 22 of section 9 to the opposite end of that section and then back again to end 22, two layers of filament 16 are uniformly laid upon spool 1 at which time switch 21 is actuated. Thus, after each two layers of filament are laid upon spool 1 switch 21 is actuated causing operation of motor 26 for a finite period of time. The operation of motor 26 changes the voltage to and torque of motor 5. It can thus be seen that the torque output of motor 5 can be increased in direct relation to the amount of filament laid upon spool 1, which is an ultimate desired result of this invention.

When spool 1 is as full of filament 16 as desired, motor 5 is turned off and coil 50 deenergized which causes switches 52 and 53 to automatically return to their normal positions against contacts 54 and 55. When this occurs current is passed through lines 59 and 100, switch 52, line 101, switch 31a; which is normally closed, i.e. against contact 102, and line 103 to energize coil 104 of relay 105. Coil 104 is connected to neutral lines 106, 81 and 107. When coil 104 is energized switches 109 and 110 are transferred from their normal positions shown in FIGURE 2 against contacts 111 and 112. When this occurs current passes from hot line 58 through lines 113 and 114, switch 109, and line 115 into line 97 thereby reversing the flow of current through capacitor 95 and motor 26 causing motor 26 to rotate in a reverse direction from before when coil 50 was energized. In order to operate motor 26 by putting capacitor 95 in the

circuit by energizing coil 88 as discussed above, current also passes through lines 113 and 120, switch 110, contact 112, line 121 and line 126 to energize coil 88.

Thus, when coil 50 is deenergized upon turning off of motor 5 to remove a full spool and replace same with an empty spool, coil 104 is energized thereby causing switches 109 and 110 to move against contacts 111 and 112 thereby energizing coil 88 and passing current to motor 26 through line 97, both of which actions cause motor 26 to operate but in the reverse direction from which it operated when coil 88 was energized by current passing through line 86, switch 70, and line 87. This rotation of motor 26 in a reverse direction causes arm 43 in contact with resistor 44 to also move in the reverse direction, i.e. move to a point where the torque of motor 5 is that desired for an empty spool rather than the point upon which it ended up which was desired for a full spool.

While motor 26 is being run in a reverse direction arm 32 (FIGURE 1) carried by shaft 27 is moved into contact with microswitches 31a and 31b (generally designated as 31 in FIGURE 1) in a conventional sequential manner.

Arm 32 first contacts switch 31b so that it moves against contact 125 thereby closing the circuit comprising hot line 58, switch 31b, line 126, and coil 88 so that coil 88 will remain energized even though arm 32 after contacting switch 31b contacts switch 31a and opens same. Opening of switch 31a deenergizes coil 104 and allows switch 109 and 110 to resume their normal positions against contact 127 and 128.

Since coil 88 remains energized through switch 31b, notwithstanding the fact that switch 31a is opened, motor 26 continues to run. However, since switch 109 is opened no current passes to the motor 26 through line 97 but instead passes from hot line 58 through lines 113, 120, switch 110, and line 130 to line 96 thereby causing motor 26 to stop moving in the reverse direction and begin again moving in the forward direction. This movement in the forward direction following the resetting movement in the reverse direction of motor 26 is utilized to take the slack out of gears 40 and 41 and other associated apparatus so that when winding upon an empty spool begins and switch 21 is tripped after two layers of filament are wound on spool 1 motor 26 and its associated apparatus are ready to respond immediately.

While motor 26 is moving forward again after the resetting reverse rotation above described member 32 first returns switch 31b to its normally open position thereby deenergizing coil 88 causing switch 99 to move against contact 91, thereby bypassing capacitor 95 and stopping the forward rotation of motor 26.

This system is now prepared to go through a similar set of steps while filling a new spool with filament. When the first two layers of filament are wound upon the new spool switch 21 is actuated thereby causing motor 26 to rotate shaft 27 further in the forward position. Although line 101 has no current therein because switch 52 has been moved against contact 56 by the energization of coil 50 as described above, switch 31a is still in the open position into which it was moved by arm 32 while filling the prior spool and arm 32 while being rotated forward during the filling of another spool resets switch 31a by moving same against contact 102 so that as soon as coil 50 is deenergized and switch 52 moves against contact 54 coil 104 can be energized.

A suitable conventional arrangement for switch 31a and 31b is that switch 31a is a latching type switch which has to be reset by pressing the reset button after the switch has once been opened and switch 31b is a microswitch biased so that its normal position is open and it will automatically return to that position when not forced closed by arm 32. The arrangement of these switches then would be such that the actuator arm for switch 31a will be contacted first by arm 32 but switch 31a will not immediately be opened, rather the actuator arm for 31a will first contact the actuator arm for 31b at which time switch

31b will be promptly closed. Upon a slight further movement of the actuator arms of switch 31a and 31b in the same direction, switch 31a is then opened. Thereafter, when motor 26 is changed so as to again rotate in the forward direction the actuator arms of switches 31a and 31b will move in the reverse direction but withdrawal of the actuator arm of switch 31a will allow the actuator arm of switch 31b to automatically resume its normally open position. Thereafter, while filling a new spool, further rotation in the forward direction of arm 32, the actuator arm of switch 31a will, by a suitably arranged appendage therefrom, contact the reset button for switch 31a causing that switch to close against contact 102.

Reasonable variations and modifications are possible within the scope of this disclosure without departing from the spirit and scope thereof.

We claim:

1. A motor means, a support member attached to said motor means, a controller attached to said motor means, said controller being adapted to control the torque of said motor means in response to the amount of material wound upon said support member, said controller comprising guide means for uniformly applying said material to said support member, a switch means, said guide means being adapted to temporarily actuate said switch means after a predetermined amount of said material has been wound about said support member, a reversible, high slip motor capable of dynamically braking itself and of being stalled indefinitely in the brake position, said high slip motor being operatively connected to the said first switch means, means for operating said high slip motor for a finite period of time after each temporary actuation of said switch means, adjustable means for controlling the power input to said motor means, and means operatively connecting said high slip motor and said adjustable means so that upon each operation of said high slip motor said adjustable means is adjusted to vary the power input to said motor means in relation to the amount of material wound upon said support member.
2. A winding device wherein an elongate material is wound upon a support member, said winding device comprising a support member, a first motor means connected to said support member, means connected to said first motor means for controlling the torque output of said first motor means in response to an increasing amount of material wound upon said support member comprising level winding guide means for uniformly applying said material to said support member, said guide means being adapted to reciprocate along the length of said support member and thereby uniformly wind said filament upon said support member, a switch means located at one end of the path of travel of said guide means and adapted to be temporarily actuated by said guide means each time it reaches the location of said switch means, a reversible high slip motor capable of dynamically braking itself and of being stalled indefinitely in the brake position, said high slip motor being operatively connected to said switch means, means for operating said high slip motor for a finite period of time after each temporary actuation of said switch means, adjustable electrical means for controlling the voltage input to said first motor means, and electrical means operatively connecting said high slip motor and said adjustable means so that upon each operation of said high slip motor said adjustable means is adjusted to increase the voltage input to said first motor means thereby responding to the increased amount of material wound upon said support member before said switch means is actuated.
3. A winding device wherein a filament is wound upon a spool, said winding device comprising a spool, a first motor means connected to said spool, said spool being rotated by said first motor means, means connected to said first motor means for increasing the torque of said first motor means in response to increasing amounts of filament being wound upon said spool comprising reciprocating mounted guide means for uniformly applying successive layers of

said filament to substantially the full length of said spool, said guide means including a support member and a rotatable member adapted to rotate said support member across which filament passes, said guide means being adapted to move said rotatable support member along the full length of said spool, a first switch means located at one end of the path of travel of said guide means and adapted to be temporarily actuated by said guide means each time said guide means moves into the area of said first switch means, a substantially instantly reversible, high slip electric motor capable of dynamically braking itself and of being stalled indefinitely in the brake position when at least one electrical component thereof is removed from its circuit, said high slip motor being operatively connected to said first switch means, a second switch means operatively connected to said high slip motor and adapted to remove at least one component of that motor from its circuit upon being tripped, a coil means associated with said second switch means and adapted to trip said switch means when energized, a capacitor means operatively con-

nected to said coil means and being adapted, after being charged, to energize said coil means by being discharged through same, an autotransformer means operatively connected to said high slip motor and to said first motor means, said autotransformer means being adapted to increase the voltage to said first motor means in response to a finite degree of rotation caused by said high slip motor during the finite period of time in which said capacitor means is discharging through said coil means, thereby increasing the torque of said first motor means by a finite increment each time said first switch means is actuated.
